STOP MOTION FOR KNITTING MACHINES

William L. Smith, Jr., and Robert H. Lawson,
Pawtucket, R. I.; said Smith assignor to May
Hosiery Mills, Nashville, Tenn., a Corporation
of Tennessee

Original application February 21, 1930, Serial No.
430,436. Divided and this application March
11, 1931. Serial No. 521,840

3 Claims. (Cl. 66—165)

This invention relates to stop motion and to belt shifting mechanism for knitting machines and is a division of our copending application Serial No. 430,436 filed February 21st, 1930, for 5 knitting machines.

An object of the invention is to provide new and improved mechanism for this purpose which will be operated upon the breaking of a needle latch or by the accumulation of yarn adjacent 10 the latches produced by any other cause.

A further object is to provide means operated by pattern controlled mechanism on the machine for changing the speed of a knitting machine or for stopping it.

15 Referring to the accompanying drawings which are made a part hereof and on which similar reference characters indicate similar parts,

Figure 1 is a view in front elevation of a belt 20 shifter and stop motion mechanism.

Figure 2, a plan view of the stop motion,

Figure 3, an enlarged detail in front elevation showing the yarn engaging detector, and

Figure 4 is a view similar to Figure 3 but in 25 side elevation with parts shown in section.

As shown in Figure 1, a main shaft 44 has mounted thereon a fast pulley 45, a slow pulley 46 and a loose pulley 47, these pulleys being driven by means of a belt, not shown and the 30 shaft 44 being connected by any well known gearing connection, not shown, with the driven parts of the knitting machine. A belt shifter 48 having two arms which extend to engage opposite sides of the belt, not shown, is provided, the arms of the shifter serving to move the belt from any one of the pulleys to another. The belt shifter is mounted upon a bracket 49 which bracket is slidably mounted upon a shaft 35 or rod 50. The bracket 49 is moved by means of a manually or automatically operated lever 51 which lever is pivoted at 52 to another bracket 53. The bracket 49 slides upon the bracket 53 having a rib 54 which engages a groove 55 provided in the upper face of the lower bracket 45. The two brackets 49 and 53 under some 50 circumstances are slidable together as a unit but at other times one may move independently of the other. Intermediate its ends the lever 51 has a triangular shaped opening 56 into 55 which extends a pin 57 carried by and laterally projecting from one side of a lever 58. The lever 58 is pivoted at 59 to the bracket 49. The lever 58 consists of a horizontal portion extending from the pivot 59 to a point near the pin 57 and from there extends at a right angle and

then terminates in a horizontally extending arm having an end 60 projecting through the machine frame. A spring 61 is attached at one end to a pin 62 secured in the bracket 49 and has its other end secured to a pin 63 fixed to 60 the lever 58. The spring tends to maintain the lever 58 in a position in which the pin 57 will be held in the upper portion of the triangular opening 56. The spring 61 also serves to hold the lever 58 in a position in which a shoulder 64 provided by a notch in the upper edge of the lever will seat against the edge of a plate 65, which plate is carried by the inner portion of the lower bracket 53. The shoulder 64 seating against the plate 65 acts as a latch to hold 70 the bracket 49 in a fixed relation with the bracket 53. When the parts are in the position just described the belt shifter may be holding the belt upon any one of the pulleys 45, 46 or 47, the pulley upon which the belt is positioned 75 being determined by means later to be described. The lower bracket 53 is provided with a hollow post or tubular extension 66 in which is received an expansion spring 67 surrounding a pin 68 which is attached to and forms part of 80 the bracket 49. The spring 67 bears at one end against the extension 66 and at its other end upon a face 69 of the bracket 49. When the shoulder 64 is released from engagement with a plate 65 the spring 67 serves to move the 85 bracket 49 with respect to the bracket 53 and this movement shifts the belt from the fast pulley 45 to the slow pulley 46 or to the loose pulley 47. Under certain circumstances it may 90 shift belt from the slow pulley 46 to the loose pulley 47. At 43 is shown a portion of a cam shaft on the knitting machine to which is secured a cam drum 70 having a cam 71 thereon which cam is maintained in constant engagement with a pin 72 depending from and carried 95 by the free end of an arm 73. The arm 73 is pivoted at 74 to a bracket 75 secured to the machine frame (Fig. 2) the pin 72 is maintained in adjustable engagement with the cam 71 by 100 means of an adjusting screw 76 carried by the bracket 53. The head of the adjusting screw is held in constant yielding engagement with the arm 73 by means of a spring 77. This spring is connected at one end to a pin 78 on the machine frame and at the other end to a pin 79 attached to the bracket 53. As may be seen the spring thus normally holds the bracket 53 in a position adjacent to the machine frame as shown in Figure 1. The bracket 49 as 105 described is slidably mounted on the bracket 53 110

having a rib 54 engaging the groove 55 in the bracket 53. The bracket 49 is also mounted to slide upon a pin or rod 80 carried by and projecting from the machine frame. The bracket 53 likewise is slidably mounted upon a pin 81 carried by and projecting laterally from the machine frame.

As shown in Figures 3 and 4 a detector 82 is mounted above the dial needles, this detector being engageable by the accumulation of yarn upon the needles due to a broken needle latch or possibly to some other causes. The detector is carried by and forms part of a plate 83 which plate is adjustably fastened to a plate 84 by means of screws 87 and 88 which pass through elongated slots 85 and 86 and engage with the plate 84. The slots 85 and 86 permit the detector plate 83 to be adjusted to any desired vertical position to position the detector point 82 at the proper position with respect to the dial needles. Plate 84 is pivoted at 89 to a block 90 which block is fastened to a sleeve or plunger 91 by means of screws 92. The sleeve 91 is slidably positioned in a longitudinal opening in a bracket 93 which bracket is fastened to the dial cap of the machine. Within the plunger 91 is a recess 94 in which is positioned a coil spring 95, the upper end of which spring engages shoulders 96 and the lower end seats upon the upper face of the dial cap. The spring tends to move the plunger 91 and the associated elements including the detector 82 to an elevated position. The block 90 has an overhanging extension 97 which is notched at 98. A lever 100 has an arm 99 which seats within the notch 98, the notch serving to retain the lever in a set position until released. The plate 84 has a bayonet slot 101 in which is received a pin 102, the pin being secured in the bracket 93, the lever arm 99 is secured to a hub 103 attached to a sleeve 104 by means of a set screw 105. The sleeve 104 is pivotally mounted upon a pin 106 which stands up from and is carried by the circular base of the machine. The sleeve has at its lower end a second lever arm 107 which is secured by means of a set screw 105. The free end of the lever arm 107 has slidably therethrough a rod 108. The rod 108 has collars 109 and 110 thereon between which the end of the arm 107 is positioned. A coiled expansion spring 111 surrounds the rod 108 between the rod 110 and the lever arm 107 and tends to move the arm to the left (Fig. 2) and into engagement with collar 109. At its other end the rod 108 is pivoted at 112 to one arm of a lever 113 pivoted at 114 to the machine frame. The other arm of the lever is provided with a key-hole slot 115, and passing through this slot is a vertically movable rod 116 having a head 117 on its upper end. The rod is reduced at 118 to provide a shoulder 119 which normally seats upon the lever 113 when positioned in the narrow portion of the key-hole slot as shown in elevated position in Figure 1. The lower end of the rod 116 is bent substantially at right angles at 102, the bent end being adapted to engage the end 60 of the lever 58. A block 121 having a plate 122 secured thereon is fastened to the machine frame, the plate serving to guide the rod 116 in its vertical movements and also to prevent the right-angled end 120 from turning.

When the mechanism just described functions as a stop motion the detector 82 is actu-

ated by an accumulation of thread or yarn adjacent the needles such as is caused by a defective needle. The accumulation of thread finally bunches until due to the rotation of the dial and cylinder the bunch of thread engages the point of the detector and thereafter continued rotation of the cylinder and dial causes the accumulated thread or bunch to swing the detector from the position shown in Figure 3, to the right, rocking the plate 84 on its pivot and moving the horizontal portion of the bayonet slot away from the pin 102, whereupon the spring 95 moves the plunger 91 carrying up with it the block 90 until it strikes the upper portion of the bracket 93 overhanging the block 90. The extension 97 of the block 90 moves up with it and this movement frees the lever arm 99 from engagement with the notch 98. As soon as the arm 99 is released from the notch 98 the coil spring 111 expands and moves the lever arm 107 to the left until it forcibly engages the collar 109 and moves the rod 108 toward the left. This swings the lever 113 upon its pivot and withdraws the narrow portion of the key-hole slot 115 from under the shoulder 119 and permits the rod 116 to fall through the enlarged portion of the key-hole slot, which portion is of course greater than the diameter of the rod 116. As the rod 116 drops down, the bent-over end 120 strikes the end 60 of the lever 58 which is projecting through the frame and rocks this lever upon its pivot 59 releasing the shoulder 64 from engagement with the plate 65. As soon as the shoulder 64 is released the spring 67 forces the bracket 49 to the right, this bracket carrying with it the belt shifter 48, moving the belt to the loose pulley and the machine is stopped. The cam 71 carried by the drum or disk 70 is adapted to engage the pin 72 at desired times and to force the same to the right, Figure 1, into contact with the screw 76. This movement carries the lower bracket 53 to the right. The movement of the lower bracket 53 is transmitted to the upper bracket 49 and the belt 120 shifter 48 either to stop the machine or to change from high speed to medium or slow speed. The speed may be automatically changed as described at any time during the knitting of the stocking, for example prior to the knitting of the heels and toes. Furthermore if it is desired to cast off each stocking, another cam may be carried by the cam disk or drum 70 to move the lever 73 to such an extent as to shift the belt from the fast pulley to the loose pulley and stop the machine. From the description just given it will be seen that although the mechanism shown is primarily intended to serve as a stop motion, in its broader aspects it serves as a belt shifting mechanism whereby the machine may be manually stopped at any time by moving the belt from the fast or the slow pulley to the loose pulley. Furthermore the speed of the machine may be reduced by manually moving the belt from the fast to the slow pulley.

It will be obvious to those skilled in the art that various changes may be made in our device without departing from the spirit of the invention and therefore we do not limit ourselves to what is shown in the drawings and described in the specification, but only as indicated by the appended claims.

Having thus fully described our said inven-

tion, what we claim as new and desire to secure by Letters Patent, is:

1. A belt shifter including a plurality of pulleys and manually operating means consisting of 5 a lever having an opening therein provided with a plurality of seats for a pin, a member having mounted thereon means for shifting a belt, said member provided with a pin, the pin received within the said opening and adapted to 10 seat in any one of the plurality of seats provided by the mentioned opening in the lever, movement of the lever in one direction camming the pin and member to such a position as to shift the belt from one pulley to another, the 15 pin when so shifted seating in another seat provided by the opening in the lever, substantially as set forth.

2. In a knitting machine, the combination 20 with a detector movable by engagement with defects in the knitted fabric of a stop motion comprising a belt shifter mounted on a bracket, a latch locking the bracket in position to hold the belt on the driving pulley, means biased to shift the bracket to move the belt to a loose 25 pulley, a lever for releasing the latch, to permit the belt shifter to move the belt to the loose pulley, said bracket being mounted upon a second bracket, and means controlled automatically

by the machine for moving said second bracket to shift the first bracket together with the belt shifter to move the belt from a fast to a slow pulley, substantially as set forth.

3. In a knitting machine the combination with 80 a detector, of a belt shifter for moving the driving belt from a fast to a loose or to a slow pulley said belt shifter comprising a bracket having a belt shifter mounted thereon, resilient means for moving the bracket to move the belt to a 85 loose pulley, a second bracket, a latch pivotally mounted on the first bracket and engageable with the second bracket to hold the belt on the fast pulley, a lever pivotally attached to said second bracket and having a socket engageable by a pin mounted in said latch, said socket having cam surfaces for operating the latch to release it when the lever is moved, movement of the lever serving to cam the locking means to unlocking position, and means operated automatically by mechanism on the knitting machine for moving the second bracket, said second bracket serving to move the first bracket to shift the belt from the fast to the slow speed 95 pulley, substantially as set forth.
